UNITED STATES PATENT OFFICE.

JOHN E. STEPHENS, OF SALT LAKE CITY, UTAH TERRITORY.

LAMP-STOVE.

SPECIFICATION forming part of Letters Patent No. 286,862, dated October 16, 1883.

Application filed May 19, 1883. (No model.)

To all whom it may concern:

Be it known that I, JOHN EDWARD STEPHENS, a citizen of the United States, residing at Salt Lake City, in the county of Salt Lake and Territory of Utah, have invented certain new and useful Improvements in Lamp-Stoves, named by me and known as "The Salamander;" and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to certain new and useful improvements in lamp-stoves for burning coal-oil or petroleum, the object being to produce a portable stove or heater adapted to be placed in the fire-box of a cooking or heating stove, whereby the expense of fuel is reduced, and the inconvenience of undue heat during the summer months avoided; and it consists in the peculiar construction and arrangement of parts, as will be hereinafter more fully described and claimed.

In the annexed drawings, which fully illustrate the invention, Figure 1 is a perspective view of my heating apparatus. Fig. 2 is a perspective view of the cover. Fig. 3 is a similar view of the device with the cover removed, showing the frame for holding the oil-mat in position; and Fig. 4 is a longitudinal section of the heater.

The letter A represents a metal tank or reservoir, in which the oil is placed. The top of the reservoir is provided with a flange, a. Over the reservoir A, resting on the flange a, is placed an oil-mat, B, which rests on and is supported by a wire frame or grate, b, in the top of the oil-reservoir, as shown in Fig. 4. This oil-mat B is composed of cotton, plaster-of-paris, and asbestos, and is for the purpose of absorbing the oil and rendering it non-explosive. The mat B is held firmly in place on the reservoir by a metal frame, C, provided with a flange, c, which rests on the edges of the mat all around, the mat being between the flanges a and c. The frame C and reservoir A are secured by bolts or rivets passing through the mat and the flanges a and c.

D represents the cover, which is placed over the frame C and rests on the flange c. This cover D is provided with air openings or holes d d around its sides for promoting combustion. In the cover D are cut two holes or apertures, 55 d d, each of which is provided with a collar, e. Over each collar e is slipped a perforated tube or flame-concentrator, E. These concentrators extend a suitable distance above the collars e e, and are furnished with air-holes f f. Around each concentrator E, and concentric therewith, is a sheet-iron drum, F, standing on legs g g, attached to the cover D, as shown in Fig. 1. The drums F F are of larger diameter than the concentrators E E, in order to leave an air-space 65 between them. The drums are raised about half an inch from the top or cover D by means of the legs g g, thus affording openings for air, thereby creating drafts and aiding combustion in the concentrators E. Over each of the concentrators may be placed, if desired, a perforated flat or cone-shaped cap, h, for the purpose of condensing the smoke. A lug, i, is cast on each end of the frame C, to which lugs a bail or handle, G, is secured, serving to render the 75 heater portable.

The heater being placed in the fire-box of a stove, the oil-mat B, which is saturated with oil from the tank A, is ignited. The flames on the surface of the mat will be directed toward and concentrated in the tubes E E by the draft through the same, and thus concentrating the heat against the bottoms of the cooking-vessels placed above the tubes on the stove, the concentration and combustion being facilitated by the drafts around the tubes E. By means of caps or extinguishers the flames can be extinguished or one side left burning.

It will thus be seen that my invention affords a simple, effective, and safe lamp or heater, 90 and one having no wick or burners.

Some of the advantages derived from this invention are that it does not heat the room in which the cooking is done, the heat being all concentrated on the vessels; it is ready for use 95 and can be put in operation almost instantly; it can be extinguished immediately, thereby economizing fuel and heat, and from its construction it is perfectly safe, the oil-mat avoiding any danger of explosion.

Having thus described my invention, what I claim as new, and desire to secure by Letters Patent, is—

1. A lamp stove or heater composed of a tank or reservoir, A, oil-mat B, frame C, having handle G, and the cover D, provided with the concentrator-tubes E and drums F, substantially as shown, and for the purpose described.
- 10 2. The combination, in a stove, with a tank or reservoir, A, having flange *a*, of an oil-mat, B, and frame C, having flange *c*, for the purpose described.
- 15 3. The combination, with the tank A, having flange *a*, the oil-mat B, and the frame C, having flange *c*, of a cover, D, having perfor-

rated concentrator-tubes E and drums F, substantially as described.

4. In a lamp-stove, the tank A, mat B, and frame C, in combination with a cover, D, having openings *d d*, provided with collars *e e*, concentrator-tubes E E, having air-holes *f f*, and drums F F, standing on legs *g g*, and the air-holes *d' d'*, substantially as shown and described.

25 In testimony whereof I affix my signature in presence of two witnesses.

JOHN EDWARD STEPHENS.
